COIN DETECTOR

Emerson A. Bolen, Morris, Ill., assignor to
Northwestern Corporation, Morris, Ill., a Cor-
poration of Illinois

Application December 26, 1929
Serial No. 416,700

11 Claims. (Cl. 194—102)

This invention relates to coin mechanisms for controlling the discharge of articles from vending machines and more particularly to coin detectors therefor, although certain features there-
5 of may be employed with equal advantage for other purposes.

It contemplates more especially the provision of simple and effective means for detecting coins of predetermined dimensions and characteris-
10 tics in the manipulation of vending mechanisms for effecting the selective discharge of articles therefrom.

Mechanical vending devices have met with in-
15 creased popularity as a distributing medium owing to the entailment of little or no labor as well as the expensive sales assistance which com-
mands a salary expenditure inconsistent with the profits derived from the sale of such merchandise. In order that vending devices may prove satis-
20 factory and profitable, it is necessary or at least highly desirable to provide means for detecting spurious coins and rendering vending machines inoperative responsive thereto for effecting the discharge of articles therefrom.

25 Further, such devices should be rendered inoperative by precluding the reception of coins while entirely deplete of articles, thereby rendering it impossible for an individual to deposit a coin without being the recipient of an article serving as an inducement for the expenditure. Additionally, the machines must be so constructed as to detect the insertion of spurious coins which are responsible for the decided pecuniary loss in vending through this mechanical medium. Coordination of these expedients is
30 requisite to the fulfillment of the successful purpose for which devices of this character are employed, namely, the provision of a profitable commercial vending medium.

40 One object of the present invention is to provide a coin detector of novel and simple construction for precluding or rendering effectless the deposition of spurious coins.

Another object is to simplify the construction
45 and improve the operation of devices of this character.

Still another object is the provision of means for detecting spurious coins and rendering devices of this character irresponsible thereto.

50 A still further object is the provision of simple means for detecting minute variances in coin thicknesses.

Still a further object is to provide novel means for positively detecting coins having an aperture or depression therein.

Other objects and advantages will appear from the following description of an illustrative em-
bodyment of the present invention.

In the drawings:

Figure 1 is a front view in elevation of a vend-
ing device having an associated coin detector
embodiment features of the present invention,
parts thereof being broken away to clarify the
showing.

Figure 2 is a sectional view taken substantially 65
along line 2—2 of Figure 1.

Figure 3 is a front view of a coin detector em-
bodying features of the present invention.

Figure 4 is a rear view of the coin detector
disclosed in Figure 3. 70

Figure 5 is a sectional view taken substantially
along line 5—5.

Figure 6 is a perspective view of a coin chute
disclosed in Figures 4 and 5.

Figure 7 is a perspective view of a lever em-
ployed in connection with the detector disclosed
in the previous figures. 75

Figure 8 is a perspective view of a plate con-
stituting the guiding means for a slide.

The preferred embodiment of the detector is 80
shown in association with a vending machine
disclosed and particularly described in applic-
ant's copending application, Serially Numbered
355,734 and filed April 17, 1929 which, briefly
described, comprises a casing 10 enveloping a 85
frame 11, which supports the coin mechanism
and its associated elements. The coin detector
consists, in this instance, of a face plate 12,
which is preferably though not essentially of rec-
tangular configuration bounded by a peripheral
edge 13. The peripheral edge 13 terminates in a
bearing surface defining a flange 14 on the ob-
verse side thereof for projection beyond the
inclined face plate 12, thereby defining a cham-
bered interior 15 which receives the instrumen-
tations therein. 95

The wide edge 16 of the face plate 12 has a
semi-elliptical opening 17 in communication
therewith and the chambered interior 15, there-
by enabling a coin chute to register therewith. 100
To this end, a substantially rectangular plate 18
having upturned edges 19 along the sides thereof
is disposed for attachment to the chambered in-
terior 15 in confronting relation with the coin
opening 17 provided therein. In consequence
thereof, the plate 18 is provided with laterally
extending flanges 20 along the sides thereof,
these being apertured as at 21 to enable the pro-
jection of fasteners such as rivets 22 there-
through. An elongated plate 23 having an out-
110

wardly directed flange 24 bent or otherwise formed along the top edge thereof, is applied to the surface of the chambered interior 15, it being provided with a semi-elliptical opening 25 conforming in contour and smaller in extent than the opening 17 for disposition in confronting communication therewith. It is to be noted that the plate 23 is apertured as at 26 to correspond with the apertures 21 in the flanges 20 of the plate 18 so that the fasteners 22 may be utilized to effect the joinder therewith to cover the opening 25 therein.

The application and attachment of the plate 18 with the edges 19 abutting against the surface of the plate 23 defines a coin chute 27 of such cross-sectional shape and extent to slidably accommodate a coin therein of predetermined shape and dimensions. Inasmuch as the flange 24 abuts against the upward edge of the chambered interior 15, an elongated slot 28 is provided therein for communication with the opening 25 and in alignment with the coin chute 27 for permitting the entrance of a coin therethrough, the plate 23 being held in position and guided along a rectilinear path by means of elongated slots 29 which register with studs 30 anchored in the face plate 12 from the chambered interior 15 thereof. Obviously, the plate 23 will be movable in a horizontal path between the limits defined by the slots 29, there being an upstanding lug 31 integrally or otherwise stamped from the chute plate 18 to serve as an anchor for one extremity 32 of a spiral spring 33 having the other extremity 34 fixed to a pin 35 and mounted proximate to the edge of the chambered interior 15 to normally urge the slide plate 23 to its extreme initial position wherein the opening 25 communicates with the opening 17 provided in the face plate 12. To this end, the edge 36 of the slide plate 23 is provided with a notch 37 for registry with the pin 35 so as to afford its extreme movement in contact with the edge 38 of the chambered interior 15 which serves as a stop therefor.

To sustain the coin within the chute 27 while the slide plate 23 is in its initial position, a coin rest comprising a lug 39 is positioned immediately below the opening 17 in vertical alignment with the entrance 28 of the coin chute 27 when assuming its initial position so that the coin will rest thereon, the lug 39 being provided with apertures therein to receive threaded studs 40 therethrough for effecting its attachment to a ledge 41 integrally formed proximate to the lower edge 42 of the chambered interior, it being spaced from the slide plate 23 for a sufficient distance to permit relative movement therebetween. The slide plate 23 is displaced along a predetermined rectilinear path within the limits of the guide slots 29, by means of a knob 43 which has a shank 44 extending through an elongated slot 45 provided in the face plate 12, for projection through an aperture 46 provided in the slide 23. The knob shank 44 which projects through the aperture 46 in the slide plate 23, is swaged or otherwise anchored thereto in any suitable manner so as to establish a rigid joinder therebetween to afford slidable movement thereof from the exterior of the face plate 12.

In order to effect the passage of the coin from the chute 27 to a coin passage 47 which is branched as at 48 for communication with a coin mechanism 49 so that the arrival of a coin in the path of the pawl 50 will permit the knob 51 to be rotated in a manner more fully described in

the aforesaid copending application, thereby rotating the article confining magazine 52 through the medium of a pinion 53 in mesh with a gear 54 constituting a face thereof.

The displacement of the coin within the chute 27 to the passage 47 is necessarily effected by sliding the plate 23 so that the chute 27 thereof will traverse a distance beyond the coin sustaining lug 39, thereby permitting the coin to drop to the passage 47 for further guidance to the coin mechanism 49. This requirement for a predetermined displacement of the slide plate 23 affords a means of rendering such movement possible responsive to a predetermined position of a detector. This detector control comprises, in this instance, a lever 55 which has upstanding confronting tangs 56 stamped from the material of the lever 55 along the edges thereof more proximate to one extremity 57 and far more remote from the extremity 58 thereof for a purpose which will appear more fully hereinafter. The tangs 56 are so spaced as to be received between the upstanding lug 31 and a confronting lug 58 formed on the chute plate 18, these being provided with aligned apertures 59 for receiving a pin 60 therethrough which serves as a fulcrum for the lever 55. With this arrangement, the fulcrum of the lever 55 defined by the aperture tangs 56 thereof, defines a short straight arm 61 in confronting relation with the chute plate 18 while the longer arm 62 thereof is slightly curved to extend a distance three-fold the extent of the arm 61.

In consequence thereof, any angular deflection or displacement of the short arm 61 will cause an opposed displacement of the arm 62 a distance proportional to their respective arm lengths. In consequence thereof, the arm 61 is provided with a concavity or impression defining a projection 63 which extends in the direction of the chute plate 18 provided with a correspondingly shaped aperture 64 therein for enabling its projection within the coin chute 27 to establish contact with a coin disposed therein.

A spring 65 having one extremity thereof anchored to the lug 31, is operatively connected to a lug 66 integrally or otherwise attached to the arm 62 to normally urge the lever 55 in a clockwise direction (viewed from Figure 5) to normally dispose projection 64 of the lever arm 61 within the coin chute 27 to partially obstruct the free deposition of the coin therein which effects the counterclockwise displacement of the lever 55 so that the extremity 58 thereof will assume its dotted line position indicated in Figure 5 responsive to the deposition of a coin of predetermined dimensions and shape therein. This brings the extremity 58 of the lever arm 62 within an unobstructed lane of travel indicated by arrows A (Figure 5). To this end, an obstruction comprising a metallic stop 67 is positioned against the edge 68 of the chambered interior 15, it being secured thereto by means of threaded fasteners 69.

As shown, the stop 67 is provided with an inclined surface 70 which defines the extent of an unobstructed lane of travel for the arm 62 of the lever 55, the region extending outwardly therefrom being provided with a flat surface, in this instance assuming the form of a slot 71, which obstructs the travel of the slide plate 23 owing to contact of the lever arm extremity 58 therewith in an indicated manner. In consequence thereof, the disposition of the lever 55 in its normal position responsive to the urge of the spring

65, will permit the slide plate 23 to be displaced (to the left, viewed from Figure 3, to the right, viewed from Figure 5) responsive to the manual manipulation of the knob 43 for only a partial 5 distance in that the lever extremity 58 engages the surface 71 of the lug 67, thereby precluding the passage of the coin to the chute 27 owing to the presence of the lug 39 in the path of the coin slot 27. Now then, the deposition of a coin possessed 10 of a thickness less than a coin of predetermined or authorized dimension, will displace the lever extremity 58 a distance insufficient to remove it from confronting relation with the obstructing surface 71 of the stop 67, thereby rendering a 15 spurious coin inoperative for effecting the discharge of an article from the magazine 52.

It is to be noted that a spurious coin having an aperture therethrough similar to or approximating Chinese coins, will be ineffectual in a like 20 manner even though the dimensions thereof conform with an authorized or recognized coin, since the projection 63 on the lever arm 61 will extend within the coin aperture, thereby failing to throw the lever extremity 58 within the lane of unobstructed travel. Owing to the proportional translation of the respective arms 61 and 62 of the 25 lever 55, very minute differences in coin thicknesses will respond to detection and preclude displacement of the lever extremity 58 the required distance to afford contact thereof with the inclined surface 70 of the stop 67 which enables the full travel of the slide plate 23 for transferring the coin from the chute 27 to the passage 48. Tests indicate and establish that coin thicknesses deficient of 5/1000 of an inch is capable of 30 detection with a device of the type herein described, while overthicknesses are detected in that the entrance slot 28 is restricted to conform substantially with the thickness of a recognized coin, 35 thereby precluding its deposition within the slot 27.

The face plate 12 with the detecting mechanism supported thereon within the chambered interior 40 15 is secured to the casing 10 in its proper position by means of fasteners such as the threaded studs 73 which project through apertures 74 provided in the peripheral edge 13 thereof. The coin chute 27 is automatically maintained closed to preclude the reception of coins therein and render the coin mechanism 49 inoperative while the 45 50 magazine 52 is deplete of articles, this being accomplished by maintaining the slide plate 23 in its extreme displacement position. In consequence thereof, coins will be incapable of introduction through the entrance 28 of the slot 27 responsive to automatic means provided to accomplish that function.

The magazine supporting shaft 76 is, therefore, 55 60 provided with a disc 75 which is selectively secured thereto for rotation in unison therewith by means of a winged nut 77. This enables the disc 75 to be adjusted relative to an indicator, in this instance a pointer 78, which terminates in a 65 depressed shank 79 for attachment to the wall of the frame 11 so that the pointer 78 will be elevated a distance therefrom sufficient to permit rotation of the disc 75 therebeneath. The disc 75 is preferably though not essentially provided with graduations 80, in this instance consecutive 70 numbers corresponding with the number of compartments 81 provided in the article confining magazine 52.

A slot 82 is provided in the disc 75 for communication with the periphery thereof so as to 75 register with a lever 83 which terminates in a

lateral extension 84 for that purpose. The lever 83 is carried by a pin 85 for pivotal movement thereon so that the lateral extension 84 will project in the slot 82 when in registry therewith to enable the counter-clockwise movement 80 (viewed from Figure 1) of the lever 83. The lever 83 projects upwardly for a distance sufficient to contact with a trip 86 carried in the path thereof by a lever 87 pivoted to the ledge 41 about a pin 88 so that the lever extremity 89 will contact the lower edge 90 of the slide plate 23. To this end, a corner of the slide plate 23 is bent upwardly to provide an upstanding lug 91 to cooperate with the lever extremity 89 when displaced in the path thereof in a counter-clockwise direction 85 (when viewed from Figure 4) thereby holding the slide plate 23 in its extreme position with the lever extremity 58 abutting against the stop 67. The lever 87 is urged to this position by the engagement of the lever 83 with the lever trip 86 responsive to the urge of the spring 92 when the lateral lever extremity 84 is in registry with the slot 82 in the indicator disc 75 coincident with the depletion of the magazine 52, thereby preventing the actuation of the slide 23 under such 90 conditions of magazine depletion.

The displacement of the slide plate 23 to its extreme position responsive to the deposition of a coin to remove or effect the discharge of the last article within the magazine 52, will enable 105 the extremity 89 of the lever 87 to assume a position behind the upstanding lug 91, thereby precluding the return of the slide plate 23 which will cover the opening 17 in the plate 12 in its extreme displaced position. The lever 87 is 110 moved in counter-clockwise direction (viewed from Figure 4) to assume a position in the path of the lug 91 to preclude the return of the slide plate 23, responsive to the counter-clockwise movement of the lever 83 (viewed from Figures 115 and 4) thereby causing the extremity thereof to engage the trip 86 for displacement in its locking position.

Various changes may be made in the embodiment of the invention herein specifically described without departing from or sacrificing any of the advantages thereof as defined in the appended claims.

I claim:

1. In a coin detector, the combination with a 125 coin chute, of a member movable a predetermined distance to pass a coin through said chute, a graduated stop in the path of said movable member, and means accentuated in responsiveness to predetermined dimensional thicknesses of 130 a coin in said chute for cooperation with said graduated stop to control the extent of travel of said movable member for the purpose of passing only proper coins, said stop comprising an obstructing surface and an inclined surface extending therefrom to displace said lever from obstruction responsive to a predetermined range of coin dimensions.

2. In a coin detector, the combination with a 140 coin chute, of a member movable a predetermined distance to pass a coin through said chute an irregular stop in the path of said movable member, and pivotal means accentuated in responsiveness to the predetermined dimensions of a coin in said chute for cooperation with said irregular stop to control the extent of travel of said movable member, said irregular stop comprising a lever obstructing surface and a lever displacing surface for the purpose set forth.

3. In a coin detector, the combination with 145

150 a lever 83 which terminates in a lateral extension 84 for that purpose. The lever 83 is carried by a pin 85 for pivotal movement thereon so that the lateral extension 84 will project in the slot 82 when in registry therewith to enable the counter-clockwise movement 80 (viewed from Figure 1) of the lever 83. The lever 83 projects upwardly for a distance sufficient to contact with a trip 86 carried in the path thereof by a lever 87 pivoted to the ledge 41 about a pin 88 so that the lever extremity 89 will contact the lower edge 90 of the slide plate 23. To this end, a corner of the slide plate 23 is bent upwardly to provide an upstanding lug 91 to cooperate with the lever extremity 89 when displaced in the path thereof in a counter-clockwise direction 85 (when viewed from Figure 4) thereby holding the slide plate 23 in its extreme position with the lever extremity 58 abutting against the stop 67. The lever 87 is urged to this position by the engagement of the lever 83 with the lever trip 86 responsive to the urge of the spring 92 when the lateral lever extremity 84 is in registry with the slot 82 in the indicator disc 75 coincident with the depletion of the magazine 52, thereby preventing the actuation of the slide 23 under such 90 conditions of magazine depletion.

- 5 a coin chute, of a member movable a predetermined distance to pass a coin through said chute, a stop having an irregular surface in the path of said movable member, an elongated lever pivoted intermediate the extremities thereof to said movable member, one arm of said lever being in operative communication with said chute, and the other arm of said lever extending in or out of line with said stop with accentuated responsiveness to a dimension of a coin for cooperation with said irregular surface on said stop to control the extent of travel of said movable member within predetermined coin dimensional limits, said last named lever arm having a tapered 10 thin edge extremity for engagement with the stop to respond differently to the irregular surfaces thereon.
4. In a coin detector, the combination with a coin chute, of a member movable a predetermined distance to pass a coin through said chute, a stop having an inclined surface ineffective to obstruct said movable member an elongated lever pivoted intermediate the extremities thereof to said movable member, one arm of said lever being in operative communication with said chute, the other arm of said lever extending in or out of line with said stop responsive to predetermined dimensional thickness of a coin to control the travel of said movable member, said last named lever arm having a tapered thin edge extremity for displacement over the incline surface of the stop, spring means for urging said movable member to its initial position, other spring means for urging said elongated lever in the effective path of said stop, said lever being translatable in the path of said inclined stop surface responsive to the insertion of a coin in said chute of predetermined dimensions.
- 40 5. In a coin detector, the combination with a coin chute, of a member movable a predetermined distance to pass a coin through said chute, a stop having an effective and ineffective portion in the path of said movable member, an elongated lever pivoted intermediate the extremities thereof to said movable member, one arm of said lever being in operative communication with said chute, the other arm of said lever extending in or out of line with the effective portion of said stop responsive to a dimension of a coin to control the travel of said movable member, said last named arm of said lever having accentuated translation responsive to said shorter arm so that slight coin variations will selectively displace said longer arm in the path of either said effective or ineffective portions of said stop, said shorter lever arm having a raised projection for contacting the surface of a coin to register with depressions therein, spring means for urging said movable member to its initial position, and spring means for urging said lever so that an arm thereof extends normally in said chute.
- 65 6. In a coin detector, the combination with a coin chute, of a member movable a predetermined distance to pass a coin through said chute, a stop having an effective and ineffective portion in the path of said movable member, an elongated lever pivoted proximate an extremity thereof to said movable member, the shorter arm of said lever being in operative communication with said chute, said shorter lever arm having a raised projection for contacting the surface of a coin to register with depressions therein, and the other arm of said lever extending in

or out of line with the effective portion of said stop responsive to a dimension of a coin within said chute to control the travel of said movable member, said last named arm of said lever having accentuated translation responsive to said shorter arm so that slight coin variations will selectively displace said longer arm in the path of either said effective or ineffective portions of said stop. 80

7. In a coin detector, the combination with a coin chute, of a member movable a predetermined distance to pass a coin through said chute, a stop having an effective and ineffective portion in the path of said movable member, an elongated lever pivoted proximate an extremity thereof to said movable member, the shorter arm of said lever being in operative communication with said chute, and the other arm of said lever having a thin edge extremity extending in or out of line with the effective portion of said stop responsive to the dimensions of a coin within said chute to control the travel of said movable member, said last named arm of said lever having accentuated translation responsive to said shorter arm so that slight coin variations will selectively displace said longer arm in the path of either said effective or ineffective portions of said stop, and means responsive to a predetermined movement thereof for precluding the return of said movable member to maintain said chute closed. 85 90

8. In a coin detector, the combination with a coin chute, of a member movable a predetermined distance to pass a coin through said chute, a stop having an effective and ineffective portion in the path of said movable member, an elongated lever pivoted intermediate the extremities thereof to said movable member, one arm of said lever being in operative communication with said chute, the other arm of said lever having a thin edge extremity extending in or out of line with the effective portion of said stop responsive to a dimension of a coin to control the travel of said movable member, spring means for urging said movable member to its initial position, and spring means for urging said lever so that the arms thereof normally extend within said chute and in the path of said stop, said last named arm of said lever having accentuated translation responsive to said shorter arm so that slight coin variations will selectively displace said longer arm in the path of either said effective or ineffective portions of said stop. 110 115 120 125

9. In a coin detector, the combination with a coin chute, of a member movable a predetermined distance to pass a coin through said chute, a stop having an effective and ineffective portion in the path of said movable member, an elongated lever pivoted intermediate the extremities thereof to said movable member, one arm of said lever being in operative communication with said chute, the other arm of said lever having a thin edge extremity extending in or out of line with the effective portion of said stop responsive to the dimensional thickness of a coin to control the travel of said movable member, said last named arm of said lever having accentuated translation responsive to said shorter arm so that slight coin variations will selectively displace said longer arm in the path of either said effective or ineffective portions of said stop, spring means for urging said movable member to its initial position, and a projection on said arm to contact with the lateral face of a coin. 130 135 140 145

10. In a coin detector, the combination with 150

a coin chute, of a member movable a predetermined distance to pass a coin through said chute, a stop having an effective and ineffective portion in the path of said movable member, an elongated lever pivoted intermediate the extremities thereof to said movable member, one arm of said lever being in operative communication with said chute, the other arm of said lever having a thin edge extremity extending in or out of line with the effective portion of said stop responsive to 10 a dimension of a coin to control the travel of said movable member, said last named arm of said lever having accentuated translation responsive to said shorter arm so that slight coin variations will selectively displace said longer arm in the path of either said effective or ineffective portions of said stop, springs means for urging said movable member to its initial position, and a projection on said arm to contact with the lateral face of a coin for registry with an 20 aperture therein.

11. In a device of the character described, the combination with a magazine for confining vendible articles therein, of a coin mechanism for controlling the discharge of the articles from said magazine, said coin mechanism comprising a coin chute, a slide for permitting the passage of the coin through said chute in an extreme position of movement, a coin detector including a lever having an arm in the path of said chute, means responsive to said coin detector lever for precluding the movement of said slide to its extreme position unless a coin of predetermined physical characteristics is deposited in said chute, and means released responsive to the total discharge of the articles from said magazine for displacement behind said slide in its extreme actuated position to preclude the return of said slide from its extreme position of movement, thereby closing said chute. 80 85 90
